Primary Examiner — John R Yeh

(74) Attorney, Agent, or Firm — Riverside Law LLP

(57) **CLAIM**

I claim the ornamental design for a sponge holder, as shown and described.

DESCRIPTION

FIG. 1 is a perspective view of a first variant of the sponge holder;

FIG. 2 is a perspective view thereof;
FIG. 3 is a top view thereof;
FIG. 4 is a bottom view thereof;
FIG. 5 is a left view thereof;
FIG. 6 is a right view thereof;
FIG. 7 is a front view thereof;
FIG. 8 is a back view thereof;
FIG. 9 is a perspective view of a second variant of the sponge holder;
FIG. 10 is a perspective view thereof;
FIG. 11 is a top view thereof;
FIG. 12 is a bottom view thereof;
FIG. 13 is a left view thereof;
FIG. 14 is a right view thereof;
FIG. 15 is a front view thereof;
FIG. 16 is a back view thereof;
FIG. 17 is a perspective view of a third variant of the sponge holder;
FIG. 18 is a perspective view thereof;
FIG. 19 is a top view thereof;
FIG. 20 is a bottom view thereof;
FIG. 21 is a left view thereof;
FIG. 22 is a right view thereof;
FIG. 23 is a front view thereof;
FIG. 24 is a back view thereof;
FIG. 25 is a perspective view of a fourth variant of the sponge holder;
FIG. 26 is a perspective view thereof;
FIG. 27 is a top view thereof;
FIG. 28 is a bottom view thereof;
FIG. 29 is a left view thereof;
FIG. 30 is a right view thereof;
FIG. 31 is a front view thereof;
FIG. 32 is a back view thereof;
FIG. 33 is a perspective view of a fifth variant of the sponge holder;
FIG. 34 is a perspective view thereof;
FIG. 35 is a top view thereof;
FIG. 36 is a bottom view thereof;
FIG. 37 is a left view thereof;
FIG. 38 is a right view thereof;
FIG. 39 is a front view thereof;
FIG. 40 is a back view thereof;

(Continued)

FIG. 41 is a perspective view of a sixth variant of the sponge holder;

FIG. 42 is a perspective view thereof;

FIG. 43 is a top view thereof;

FIG. 44 is a bottom view thereof;

FIG. 45 is a left view thereof;

FIG. 46 is a right view thereof;

FIG. 47 is a front view thereof; and,

FIG. 48 is a back view thereof.

The broken lines form no part of the claimed design.
